VARIABLE WATER TANK

Ferdinand H. Heine, Milwaukee, Wis., assignor to
Koehring Company, Milwaukee, Wis., a corpora-
tion

Application February 1, 1928, Serial No. 251,191

4 Claims. (Cl. 221—95)

It is today a recognized fact in the art of concrete mixers and paving machines, that water from a water supply or measuring tank should be delivered to the mixing drum as expeditiously as possible. The now known types of water tanks commonly employed in commercial practise avail of the head created by positioning the tank above the point of entry of the water in the mixing drum for causing the said water to flow from the tank into the drum, and I do not propose to depart from this idea. However, the primary object of this invention is to provide a water tank that will supply water to a mixing drum in a constant column free from air bubbles and the like. This feature is highly important inasmuch as conditions very often arise in connection with the use of the now known type of tanks that are not altogether satisfactory. Inasmuch as the tank is availed of to supply a measured quantity of water to the mixer, the drainage of the last bit of water from the tank is usually accompanied by whirlpools, gurgles, and the like, which seriously delay the discharge of the fluid into the mixing drum.

In providing a tank that will accomplish the object above set forth, it is essential that the tank be capable of supplying variable measured quantities of water to a mixing drum, and it is also desirable that such a tank be adapted for cooperation with the conventional three-way valve mechanism employed in the construction of mixing machines, such a valve being clearly shown in the patent to Lichtenberg, 1,525,100. Bearing the above in mind, my novel water tank comprises generally, a cup member having a funnel shaped bottom with an opening therein which functions as the inlet and outflow opening of the tank. A casing is positioned around the cup member and is adjustable so that the space above the opening in the cup member may be varied as the occasion demands. Upon each cycle of operation of the water tank the latter will deliver that amount of water contained therein above the opening in the cup member which amount will be varied by adjustment of the casing. By providing the opening in the funnel portion of the cup member with a cover spaced therefrom, formation of whirlpools and like conditions are positively inhibited, and the location of the cup with respect to the discharge opening insures a steady column of water during the entire period of discharge from the tank.

Carrying out my inventive idea more specifically, I support the casing on rack members which are adjustable through appropriate gear and

worm mechanisms that may be operated to adjust the position of the tank, and a more detailed object of the invention is to provide means for locking the tank in any one of its adjusted positions.

A particularly noteworthy feature that arises in connection with the use of my variable water tank, is that it is not necessary to position the latter a considerable distance above the point of water entry into the mixing drum so as to create a large head. The construction of the cup member insures the steady delivery of the water into the drum so all that is requisite in the relationship between the water tank and the mixing drum is that the discharge opening in this cup member be positioned above the point of entry of the water into the said drum. This feature assumes still greater importance when it is considered that in the construction of concrete mixers, it is often undesirable to place the water tanks at an extremely high point in the construction thereof which high point would otherwise not exist.

In the art of concrete mixing it is very important that a measured quantity of water be added to the solid aggregates, the quantity of water added of course depending upon the mix being used. It is highly important that the amount of water thus added should be the same for each batch. It often happens that the mixer upon which the water tank is mounted must stand on an inclination, thereby tilting the water tank. Under such conditions, using old types of water tanks, the quantity of water supplied to the mixer for each batch may be altered and become inaccurate due to tilting of the water tank.

An important object of my invention, therefore, is the provision of novel means associated with the water tank which will insure the delivery of a predetermined quantity of water even though the water tank is inclined to the horizontal.

Further and more detailed objects and advantages will in part become apparent and in part be hereinafter stated as the description of the invention proceeds.

For a full and more complete understanding thereof, reference may be had to the following description and accompanying drawing, in which

Figure 1 is a view showing my water tank applied to a paving machine, the paving machine being shown diagrammatically.

Figure 2 is a view showing the relationship of the water tank to the mixing drum, parts being

broken away and shown in section to more clearly bring out the details.

Figure 3 is a detail showing of the mechanism for adjusting the position of the casing.

5. Figure 4 is an enlarged detail view in perspective of the cup member and its connection with a three-way valve, parts being broken away to more clearly bring out certain features.

10. While a preferred form of the invention is herein set forth, it is to be understood that I am not to be limited to the exact constructions being illustrated and described because various modifications of these details may be provided in putting the invention into practise within the 15 purview of the appended claims.

20. A paving machine is shown diagrammatically in Figure 1 and includes a mixing drum A mounted in the conventional frame work of the machine and has an opening B by which the drum is loaded. One end of a pipe line 1 projects into the opening B which line carries water from my novel variable water tank designated generally by the reference character C to a mixing drum. A three-way valve D is included 25 in the line 1 intermediate the tank C and opening B. A main water supply line 2 is also connected with the three-way valve D and supplies water to the tank C. The particular construction and operation of the three-way valve 30 D is clearly set forth in the patent previously referred to, and it suffices to say that this valve may be operated either to permit water to flow from the supply line 2 into the tank C or may be further operated to permit water from the tank 35 C to pass into the mixing drum A.

36. Upstanding from the valve D is a length of pipe 3 the end of which terminates in a cup member 4 having the funnel shaped portion 5. In the interior of the cup 4 a cover 6 is provided above 40 the opening in the funnel portion 5 and the said cover is spaced above the opening by any preferred supporting means such as the members 7.

45. Appropriately mounted on the frame work of the machine are slide ways 8 having grooves 9 therein in which racks 10 are adapted to move in either direction. Projecting horizontally from the slide ways 8 are supporting ears 11 which have pivotally mounted in their free ends a shaft 12 which may be operably rotated by any suitable 50 operating means such as a hand wheel 13. The hand wheel 13 may be provided with openings 14 which are adapted to receive one end of a locking bail, the other end of which is insertable in an opening 15 in one of the ears 11. The shaft 12 55 has adjacent to each end worms 16 which are in operative engagement with complementary worm gears 17 mounted on shafts 18 which carry pinions 19 in engagement with the racks 10. By reference to Figure 3 it is apparent that the hand wheel 13 may be operated to cause vertical movement of the racks 10 and the same wheel may be locked in any position desired to hold the racks 60 in position.

65. At their upper ends the racks 10 carry there- 65 between a casing 20 which has an opening 21 in the lower end thereof through which the pipe 3 passes. The relationship between the pipe 3 and casing 20 is such that relative motion between these parts is provided for. As the casing 20 is to 70 contain the fluid, sealing means between these parts may be provided as shown at 22. Inasmuch as the casing 20 is carried by the racks 10, the position thereof with respect to the cup member 4 may be varied by suitable operation of the hand 75 wheel 13. A means for draining all the fluid from

the casing 20, should the occasion arise for such action, is provided in the form of a valve in the bottom of the casing as shown at 23.

80. In the operation of my novel water tank, water is injected thereinto under pressure through the three-way valve D and pipe line 3 and passes up over the cup member 4 and fills the casing 20 an air vent 26 being provided at the upper portion thereof which allows air to pass therethrough but prohibits the passing of water as is common in such constructions. Upon proper operation of the three-way valve D that water contained in the tank above the opening in the funnel portion 5 will pass therefrom in a constant even stream of water to the mixing drum A. Obviously the 85 position of the casing 20 with respect to the cup member 4 determines the amount of water delivered with each cycle of operation of the tank. The casing 20 may be provided with suitable indicia to indicate the amount of water to be delivered by the tank, as shown at 24. The funnel portion 5, together with cover 6, insures the 90 constant flow of water by obviating any whirlpools or gurgling conditions.

95. As has been hereinbefore pointed out, one of the objects of the instant invention is the provision of a water tank which will deliver substantially equal quantities of water for a given setting of the tank even though the tank be inclined with respect to the horizontal. A brief explanation 100 of how my novel tank brings about this condition will now be given.

105. In the case of the common water tank wherein the discharge pipe 3 is used without the supplementary parts 4, 5, and 6, if the tank is tilted the water seeks the level at the lowest part or edge of the discharge pipe. It can readily be understood that the quantity of water thus delivered from the inclined tank will be greater than the quantity which would be delivered if the tank 110 were standing upon level ground. In the present invention the discharge pipe 3 has been equipped with a cup-shaped member 4 having substantially the same diameter as the tank 20. If the tank is 115 now tilted, the water will seek the level of the lowest point of the upper edge of the cup member 4. Since the cup member 4 has nearly the same diameter as the tank 20, only a small annular ring of water between the cup member 4 and the tank 20 will be discharged in addition to the 120 predetermined quantity. By making the cup member 4 substantially the same size as the tank 20, the additional quantity of water thus discharged will be negligible and the tank will deliver 125 equal quantities of water whether the same is in a horizontal or inclined position, for all practical 130 purposes.

135. Having thus described my invention, what I claim as new and desire to secure by Letters Patent in the United States, is:—

1. Water tank construction of the class described, comprising, in combination, an open topped cup member having a funnel portion with a discharge opening in its bottom, a cover for said discharge opening spaced slightly therefrom, and a casing surrounding the cup member and vertically adjustable with respect thereto, there being only a slight space between the outer wall of the cup member and the inner wall of the casing.

140. 2. Variable water tank construction of the class described, comprising, in combination, a casing having an opening in one end thereof, a tube passing through the opening and having an opening interiorly of the casing and terminating in a cup member having funnel portion, said tube afford- 145

ing the sole water inlet and outlet for the casing the annular wall of the cup member being closely adjacent the inner wall of the casing, means for adjusting the casing with respect to the cup member and tube, and means for determining the direction of the flow of water through the said tube.

3. In a liquid measuring device, a substantially vertical closed tank having an air vent at its top, 10 a pipe slidably projected into the interior of the tank through an opening in its bottom, said pipe affording a common inlet and outlet for the tank, a funnel shaped enlargement at the upper end of the pipe within the tank, an annular flange extending upwardly from the peripheral edge of the funnel shaped enlargement and lying closely adjacent to the inner wall of the tank, and means to adjust the position of the tank with respect to the pipe and its associated elements to measure 15 the quantity of liquid to be discharged, the possible error from the desired quantity being that

amount contained in the space between the annular flange and the inner wall of the tank and lying between the plane of the upper edge of the annular flange and a horizontal plane common to the lowermost portion of the annular flange upper edge whereby the possible error is maintained at a negligible minimum.

4. A water tank construction of the class described, comprising, in combination, a casing, a cup member within the casing and having a funnel portion with a discharge opening therein for the discharge of a measured quantity of liquid therefrom a covering for the opening spaced slightly therefrom for preventing the formation of a vortex, the funnel portion of the cup forming the bottom of the liquid chamber within the top of the casing, the outer end of the casing being closed to prevent the escape of liquid therethrough, whereby a constant and even flow of liquid is maintained.
